CASTING STEEL INGOT

Lewis B. Lindemuth, Port Washington, N. Y.

Application May 26, 1936, Serial No. 81,806

9 Claims. (Cl. 22—216)

In certain previous applications, Ser. Nos. 712,-
729 and 712,730, filed February 24, 1934, I have
described apparatus and processes of casting in-
gots by which to eliminate or greatly reduce the
usual piping and segregation which have necessi-
tated the cropping of a considerable percentage
at the upper end.

The present invention is directed to similar
purposes. Embodiments of the invention are
10 illustrated in the accompanying drawing.

Fig. 1 is a vertical section through the up-
per part of an ingot mold; Fig. 2 is a similar
view illustrating a modification and Fig. 3 is a
plan of the retainer of Fig. 2.

15 The purpose of the invention is to retain the
heat in the top part of the cast metal so as
to keep it fluid. I propose for this purpose to
apply on top of the hot metal 1 in the ingot
mold 2 a layer of ground cork 3.

20 This may be ground to any size, from dust to
say particles of one-half inch. In order to re-
tard the normal burning rate of the cork it is
preferably impregnated by admixture with a
small amount of water glass or silicate of soda;
25 which can vary, for example, from five to twenty
per cent by weight of the cork. Insofar as we
keep the surface of the molten metal deoxidized,
it will solidify less rapidly than an oxidized sur-
face. It is preferable, therefore, to incorporate
30 into the cork-water glass mixture a small
amount, say one per cent, of some deoxidizing
agent such, for example, as ferro-silicon or pow-
dered aluminum. As the cork burns the deox-
idizer falls on to the surface of the liquid metal
35 and prevents the formation of a film of oxide
on it. The cork, of course, is a heat insulating
material and itself assists in maintaining a re-
ducing or non-oxidizing atmosphere on top of the
ingot.

40 A great advantage in the use of cork arises
from its lightness. The total carbon content of
the weight of cork used is insufficient to alter the
composition of the top of the ingot. This is true
even though the ingots are refilled, as described
45 in my application (712,729), and the metal for
refilling poured through the cork or mixture on
the top of the ingot.

Using the mixture of cork, silicate of soda, and
50 ferro-silicon on an ingot twenty inches square,
a quantity between one-half and one cubic foot
is sufficient to maintain the top of an ordinary
open-hearth steel ingot fluid for a period of
thirty to sixty minutes. Such a quantity of the
55 mixture represents a layer varying from about
two to four and one-half inches in depth.

The invention has particular value in casting
ingots of rimming steel. By maintaining the
surface in an unoxidized condition and insulated
against cooling losses, the steel will remain fluid
and will rim for a longer period, therefore pro-
ducing a thicker skin on the ingot. In such
steel there is a continued circulation of gases.
The cork layer by extending the period of fluidity
also extends the period during which the circula-
tion continues. The lightness of the cork 10
tends to prevent its being drawn down into the
metal by the circulatory movement thereof. And
the quantity of carbon contained is so slight, as
explained above, as not to affect the composi-
tion of even the upper part of the ingot.

15 Other materials have been proposed and even
used for similar purposes but they have burned
away too quickly or have supplied too great a
quantity of carbon or have presented other dis-
advantages in casting ordinary steel and have
been practically useless in casting rimming steel.

20 Where there is to be a second teeming of hot
metal into the top of the ingot, I preferably use
the scheme shown in Figs. 2 and 3. A retainer
4 having a widened base 5 is placed on top of
the primary teeming. It fits loosely in the mold
25 and floats on the metal, its broadened base en-
suring that it shall enter only to a slight depth
into the metal. The layer of cork or mixture
3 is applied to the surface of the metal within
the retainer 4 and the secondary teeming is
30 poured through said layer. This is the method
of my above cited application (712,729) with
the addition of the layer 3 to hold the heat.

35 Various other modifications may be made by
those skilled in the art without departing from
the invention as defined in the following claims.

I claim:

1. The method of casting steel ingots which
includes pouring the molten steel into the ingot
40 mold and applying to the top a layer of ground
cork to retard the cooling of the top of the cast
metal.

2. The method of casting steel ingots which
includes pouring the molten steel into the ingot
45 mold and applying to the top a layer of ground
cork mixed with a combustion retardant to re-
tard the cooling of the top of the cast metal.

3. The method of casting steel ingots which
includes pouring the molten steel into the ingot
50 mold and applying to the top a layer of ground
cork mixed with a deoxidizing agent to retard
the cooling of the top of the cast metal.

4. The method of casting steel ingots which
includes pouring the molten steel into the ingot 55

mold and applying to the top a layer of ground cork to a depth of about two to five inches to retard the cooling of the top of the cast metal.

5. The method of casting ingots of rimming steel which includes pouring the molten steel into the ingot mold and applying ground cork to the top to retard the cooling of the top of the cast metal and extend the period of rimming.

6. The process of claim 1 followed by a second ¹⁰ pouring of molten steel through the layer of cork.

7. The process of claim 1 followed by the application of a floating retainer and a second pouring of molten steel through the layer of cork ¹⁵ within the retainer.

8. The method of casting steel ingots which

includes pouring the molten steel into the ingot mold and applying to the top a layer of ground cork impregnated with silicate of soda to the extent of about 5 to 20 per cent by weight of the cork to retard the cooling of the top of the cast ⁵ metal.

9. The method of casting steel ingots which includes pouring the molten steel into the ingot mold and applying to the top a layer of ground cork impregnated with silicate of soda to the ¹⁰ extent of about 5 to 20 per cent by weight of the cork with which is incorporated a small percentage of a deoxidizing agent to retard the cooling of the top of the cast metal.
